graphie m. b. H., Berlin, Germany, a corpora-
tion of Germany

Application April 6, 1934, Serial No. 719,285
In Germany April 6, 1933

9 Claims. (Cl. 250—27)

The present invention relates in general to receiving circuits, and in particular to receiving circuits comprising tubes operated according to the so-called "retarding field" method.

5 As it is well known in the art, the so-called retarding field circuit, as investigated by Barkhausen and Kurz, Gill and Morrell and others, is characterized by the application of a high positive potential E_g to the intermediate or grid electrode of a discharge tube comprising at least 10 three electrodes, while a polarizing potential E_b , preferably of a small negative value, is applied to the outer electrode, which hereinafter is referred to as "retarding electrode". If the potential E_b is sufficiently negative, all the electrons, 15 after having passed through the interstices of the grid electrode, are slowed down and caused to travel in reverse direction towards the intermediate electrode. If the potential of the retarding electrode becomes more positive, a current i_b , 20 which may be termed the retarding current, begins to flow to the retarding electrode. The diagram representing the function $i_b=f(E_b)$ hereinafter will be referred to as the "retarding current 25 characteristic". If the potential E_g of the intermediate electrode is sufficiently high, the cathode emits a constant or saturation current which is 30 independent of any variation of the voltages applied to the cold electrodes, provided that the grid potential never grows less than the saturation voltage. In this case the sum of the currents flowing to the intermediate or grid electrode (i_g) and to the retarding electrode (i_b) is 35 equal to the constant saturation current. This relation may be expressed by the differential equation: $d_i_g - d_i_b$. This expresses in an obvious form, that the retarding current is subtracted from the grid current. Therefore the 40 retarding current characteristic is a reflected image of the grid current characteristic, which represents the relation between the retarding potential E_b and the grid current i_g . It is obvious from this that the existence of a retarding current is the supposition for the possibility to control the discharge in a retarding field tube. Experimental investigations have proved that the 45 rectifying effect of the retarding field tube depends upon the curvature of the discharge characteristic. Therefore the rectifying action of a 50 retarding field tube or "retarding audion" is not limited to extremely high frequencies but is also applicable to lower frequencies. Usually the control voltage to be demodulated is applied to the 55 retarding electrode and the power consumed in

the input circuit is taken from the control voltage source.

The principal aim of the present invention is to dispense with the control power consumption.

Another object is to provide a satisfactory receiving circuit for all wavelengths used in radio communication service.

Other objects will become apparent in the following detailed description in connection with the accompanying drawings, wherein:

Fig. 1 represents the characteristic curves of a retarding field tube;

Figs. 2 and 3 are schematic wiring diagrams of receiving circuits according to the invention;

Fig. 4 shows a special construction of an electrode system;

Fig. 5 is a wiring diagram of a modified receiver; and

Fig. 6 is a circuit diagram of an ultra short wave receiving set.

The present invention is based on the fact that, due to the relation between the currents flowing to the intermediate or grid electrode and to the retarding electrode mentioned above, the current variations caused in the circuits connected to these electrodes by the rectifying action of the tube are equal in amount but of opposite direction. Reference is taken now to the Fig. 1, wherein the retarding current i_b and the grid current i_g are plotted against the retarding electrode voltage E_b . According to the present invention the control voltage is applied not only to the retarding electrode but also to the intermediate or grid electrode. In this way the current variations compensate each other with regard to the control voltage, i. e. the internal input impedance of the tube is infinite and no control power is consumed at all.

For a better understanding of the invention and for an illustration of a practical form of circuits in which it may be embodied, reference may be had to Fig. 2, wherein the wiring diagram of a receiver is represented. The receiver comprises a tube V containing a filamentary cathode K, a grid electrode G and a retarding electrode B. A high positive voltage is applied to the grid G by the battery E_g , while the retarding electrode B is negatively biased by the battery E_b . The radio frequency signals collected by the antenna system A are induced in the input circuit E and simultaneously supplied to the retarding electrode B and, by means of the condenser C, to the grid electrode G, so that the power consumed in the retarding electrode circuit is restored from the positively charged grid electrode. The condenser

C serves only to separate the different unidirectional voltages applied to the grid and the retarding electrode and should offer a low impedance path to the radio frequency waves. In order to prevent the radio frequency current from leaking away into the grid circuit, a high frequency choke coil D may be inserted in the grid circuit.

By properly adjusting the biasing potential of the retarding electrode E_b the operating point is located near the upper or the lower bend of the characteristic curve, e. g. on point *a* or *b* in Fig. 1. Then a rectification of the radio frequency signals takes place, whereby the modulation frequency impressed on the carrier wave may be taken off by means of a low frequency transformer T inserted in the grid circuit.

A modified wiring diagram of a receiving circuit is illustrated in Fig. 3. The radio frequency signals collected by the antenna A and induced in the input circuit E are supplied directly to the grid electrode and through a condenser C to the retarding electrode. The primary coil of the transformer T is bridged by a by-pass condenser C' providing a low impedance alternating current path for the incoming radio frequency. The retarding electrode biasing potential is supplied through a choke coil D preventing the high frequency from leaking away into the battery E_b .

A full compensation for the control current is accomplished only if the condenser C acts as short-circuit for the control frequency. If the capacity C, however, gradually is diminished beginning from very large values, a phase displacement takes place between the alternating voltages supplied to the retarding electrode and to the grid, which causes self-excitation of the circuit. Therefore, when the condenser C is made variable, the excitation may be adjusted in an exceedingly simple and comfortable manner and the sensitivity of the retarding audion thereby considerably increased.

In the Figs. 2 and 3 the condenser C is depicted as a separate circuit element. If the variation of the regenerative effect is dispensable, the condenser C may be located within the evacuated container or even constructively combined with the electrodes. This arrangement may be of particular advantage when extremely high frequencies are used. A practical form of an electrode system according to this invention is schematically illustrated in Fig. 4. The retarding electrode B forms the one condenser armature, while the other consists in a metal tube R, which is slipped over the retarding electrode B and is insulated therefrom by the dielectric D. The metal tube R is immediately connected to the grid electrode G.

In practice the exact adjustment of the retarding potential by means of the battery E_b means an additional voltage source, which may be avoided by connecting the retarding electrode through a high ohmic resistance to a positive potential. This is illustrated in Fig. 5, which is a modification of the circuit diagram shown in Fig. 3. The retarding electrode B is connected through the high frequency choke D and the high resistance W to the positive terminal of the grid battery E_g . When the resistance W is variable, the operating point may be easily adjusted to the optimal position. In order to draw a rectified current as large as possible, the resistance W is short-circuited for the modulation frequency. For this reason the resistance W is bridged by a very large capacity C'.

The method of controlling a retarding field

tube without any power consumption is of particular advantage in the ultra short wave range. Fig. 6 illustrates a receiving circuit diagram especially adapted for extremely short wave work. The resonance system comprises a lecher parallel wire system L, L', which is tuned by slidable reflecting bridges R and R' and which is excited by a dipole antenna D_i. In the voltage loop the tube V is located, the grid and the retarding electrode of which are capacitively connected within the bulb. Both electrodes are continued by the lecher wires L, which supply biasing potentials to these electrodes. The filament is interconnected between the lecher wires L' serving as heating current leads. The retarding electrode biasing potential is developed across the high resistance W, which is paralleled by the condenser C'' of very large capacity. The modulation frequency may be taken off from the grid circuit by means of the low frequency transformer T, the primary coil of which is bridged by the by-pass condenser C' forming a radio frequency short circuit. When decimeter waves are received, regeneration may be obtained by adjusting the grid potential E_g .

What is claimed is:

1. Radio receiving apparatus for ultra short wave work comprising a retarding field tube having a cathode, a grid electrode and a retarding electrode, a condenser interconnected between the grid and the retarding electrode, and a parallel wire system, the cathode being inserted into one parallel wire and the retarding electrode and the grid being inserted into the other parallel wire.

2. In combination, an electron discharge device having within an envelope an anode, cathode and control electrode, means for applying a high positive potential to said control electrode and a much lower potential to said anode relative to said cathode, a metallic element within said envelope in juxtaposition to said anode and forming therewith a condenser, a direct connection between said control electrode and said metallic element, and a high frequency tunable input circuit between said cathode and one of said other electrodes.

3. In a high frequency circuit, an electron discharge device comprising within an envelope, a cylindrical anode, a straight linear cathode within said anode and concentrically positioned with respect thereto, and a control electrode located between said cathode and said anode and extending the length of said anode, means for supplying a high positive potential to said control electrode and a much less potential to said anode relative to said cathode, a cylindrical metallic element in juxtaposition to said anode and forming therewith a condenser, one terminal of said control electrode being connected to one end of said element and the other terminal of said control electrode being connected to the other end of said element.

4. An ultra short wave receiver comprising an electron discharge device having within an envelope, a cathode, an anode and a control electrode between said anode and cathode, means within said envelope for capacitively coupling said control electrode and anode together, a lecher wire system comprising two parallel wires and a movable condenser bridge across said wires, said cathode being connected to one of said parallel wires and said control electrode to the other of said parallel wires.

5. An ultra short wave receiving system hav-

ing in combination, an electron discharge device comprising within an envelope, a cylindrical anode, a straight linear cathode within said anode and concentrically positioned with respect thereto, and a control electrode located between said cathode and said anode and extending the length of said anode, a cylindrical metallic element in juxtaposition to said anode and forming therewith a condenser, one terminal of said control electrode being connected to one end of said element and the other terminal of said control electrode being connected to the other end of said element, a two parallel wire system having movable condenser bridges substantially at both ends thereof, said cathode being serially connected in one of said parallel wires, and the capacitive coupling between said control electrode and anode being serially connected in the other of said parallel wires, and means for supplying a high positive potential to said control electrode and a much smaller potential to said anode relative to said cathode.

6. An ultra short wave receiving system having in combination, an electron discharge device comprising within an envelope, a cylindrical anode, a straight linear cathode within said anode and concentrically positioned with respect thereto, and a control electrode located between said cathode and said anode and extending the length of said anode, a cylindrical metallic element in juxtaposition to said anode and forming therewith a condenser, one terminal of said control electrode being connected to one end of said element and the other terminal of said control electrode being connected to the other end of said element, a two parallel wire system having movable condenser bridges substantially at both ends thereof, said cathode being serially connected in one of said parallel wires, and the capacitive coupling between said control electrode and anode being serially connected in the other of said parallel wires, and means for supplying a high positive potential to said control electrode and a much smaller potential to said anode relative to said cathode, an audio frequency transformer having primary and sec-

ondary windings, a utilization circuit, said primary winding being in circuit with one of said parallel wires and said secondary winding being coupled to said utilization circuit.

7. An ultra short wave receiver having, in combination, an electron discharge device having within an envelope an anode, cathode and control electrode, means for applying a positive potential to said control electrode and a much lower potential to said anode relative to said cathode, means for capacitively connecting said anode and control electrode together, a parallel tunable resonant circuit, one terminal of which is connected to said cathode and the other terminal to one of said other electrodes, an antenna coupled to said parallel resonant circuit, and a utilization circuit coupled to said connection from the resonant circuit to said cathode.

8. In combination, in a receiver, a braking field type of electron discharge device having within an envelope an anode, cathode and control electrode, means for applying a high positive potential to said control electrode and a much lower potential to said anode relative to said cathode, a capacity connecting said anode and control electrode together, a high frequency tunable input circuit, a radio frequency connection between said cathode and input circuit, and a connection devoid of concentrated reactance between said input circuit and one of said other electrodes, and a high frequency choke coil between said remaining electrode and said means.

9. An ultra short wave receiver comprising an electron discharge device having within an envelope, a cathode, an anode, and a control electrode between said anode and cathode, means within said envelope for capacitively coupling said control electrode and anode together, a lecher wire system comprising two parallel wires and a movable condenser bridge across said wires, said cathode being connected to one of said parallel wires and said anode to the other of said parallel wires.
